UNITED STATES PATENT OFFICE.

LESLIE W. CLAYBOURN, OF CINCINNATI, OHIO.

APPARATUS FOR CURVING PRINTING-PLATES.

1,318,968.

Specification of Letters Patent.

Patented Oct. 14, 1919.

Application filed March 9, 1917. Serial No. 153,731.

To all whom it may concern:

Be it known that I, LESLIE W. CLAYBOURN, a citizen of the United States, residing at Cincinnati, in the county of Hamilton and State of Ohio, have invented certain new and useful Improvements in Apparatus for Curving Printing-Plates, of which the following is a specification.

My invention relates to apparatus for curving printing plates, and is especially useful for curving printing plates employed in multi-color printing, in which a plurality of plates are employed for printing different colors, the impressions of which are intended to register with each other, and is also applicable in other relations where maintenance of relations of printing lines during curving of the printing plate is to be effected, or in which the spacings between printing lines of the printing plate, when curved, shall be the same as the spacings between said printing lines when said plate was in the flat.

The invention consists in providing means for curving the printing plate, so that its printing size will be maintained; and further in providing means for curving the printing surface and its backing, so that distortion of the printing lines for printing purposes is avoided.

The invention consists further in providing means for heating the elements of the printing plate and bending the same while heated with the ends thereof held against separating movement, whereby rearrangement of the material composing the backing of the printing plate is effected, and distortion of the printing lines is avoided; further in providing means for applying pressure to the curved printing plate; further, in providing means for applying said pressure as a progressively acting pressure along the line of curvature of the plate; and, further, in providing means for applying said progressively acting pressure reciprocatingly.

The invention consists further in providing cooling means for the printing plate during pressure application thereon; further, in providing means for curving the plate comprising a flexible band and mold-sections connected with the respective ends of said bands, said mold-sections movable toward each other for wrapping said flexible band about said mold-sections with the printing plate being curved between the

flexible band and the mold-sections; further, in providing means whereby the flexible band and mold-sections with the curved printing plate therebetween are rolled reciprocatingly for fixing the inner face of the printing plate as a curved surface curved along the periphery of the sector of a cylinder.

The invention consists further in providing means whereby end pressure is arranged to be exerted simultaneously upon both ends of the printing plate to be curved, and the intermediate portions of the printing plate are curved about mold-sections.

The invention will be further readily understood from the following description and claims, and from the drawings, in which latter:

Figure 1 is a side elevation of an exemplified machine embodying the invention, showing the mold-sections in actuated relation in full lines for curving the printing plate, and in separated relation in dotted lines.

Fig. 2 is a plan view of the same, showing the mold-sections in actuated relation.

Fig. 3 is a plan view of the same, with the mold-sections in separated relation, and showing the printing plate about to be curved.

Fig. 4 is an end elevation of my improved device, partly broken away.

Fig. 5 is a cross-section of the device taken on the line 5—5 of Fig. 1, partly broken away, with the gage and presser devices in raised relations.

Fig. 6 is a cross-section of the same on the same section line, partly broken away, with the mold-sections open, and the gage and presser devices in active relation.

Fig. 7 is a longitudinal vertical section of the exemplified device, partly broken away, showing the plate bent about the form and one end of the flexible band released from the mold, and shown partly laid back.

Fig. 8 is a plan view of a printing plate about to be bent.

Fig. 9 is a longitudinal section of the same, taken on the line 9—9 of Fig. 8.

Fig. 10 is a cross-section of the same taken on the line 10—10 of Fig. 8, the back of the plate being provided with longitudinal depressions.

Fig. 11 represents a central vertical longitudinal section of the device, taken on the line 11—11 of Fig. 3, partly broken away,

with the mold-sections separated, and a printing plate on the flexible band about to be bent.

Fig. 12 is a similar view, showing the 5 mold-sections rolled part way toward each other and equally contacting the respective ends of the printing plate.

Fig. 13 is a central longitudinal section 10 of the bent plate as the same is received off the bending-mold, the backing of the plate being provided with cross-ribs.

Fig. 14 is a similar view of the printing plate when trimmed.

Fig. 15 is a cross-section of the bent plate 15 whose backing is provided with longitudinal ribs.

Neither the method of forming the printing plate herein shown and described, nor the printing plate formed by the improved 20 device or the method is herein claimed, the method and printing plate being shown, described and claimed in copending applications, respectively Serial Nos. 145,881 and 153,732, respectively filed February 1, 1917, 25 and March 9, 1917.

The heating means herein shown and described are not herein independently claimed, the said heating means being shown, described and claimed in a copending application 30 Serial No. 153,733 filed March 9, 1917.

The printing plate to be curved is exemplified as one which is first formed flat and is shown at 21. It is provided with a printing surface 22. It may comprise a printing shell 23 and a backing 24, rigidly connected. Its margins are preferably provided with bearers 25, 26, separated from the printing surface by grooves 27, 28, the bearers 25, being exemplified as at the ends 35 of the printing plate, representing its top and bottom when secured to the plate-cylinder in the printing press, the bearers 26 being exemplified as the side bearers. The bearers are useful for receiving the edge 40 thrusts and the margin portions of the surface contacts in the curving of the printing plate for protecting the printing surface.

If desired, the rear face of the backing of 50 printing plate may be provided with recurrent depressions 29, exemplified in Figs. 13 and 14 as grooves, forming ribs extending crosswise of the curvature of the printing plate, and in Figs. 10 and 15 as grooves forming ribs extending lengthwise of the 55 curvature of the printing plate.

The printing shell is, in practice, formed 60 of electrodeposited metal, usually copper, deposited on the matrix in electroplating, and the backing is preferably of a material having a lower fusing point than the fusing 65 point of the printing shell, poured upon the printing shell and intimately connected therewith. The printing plate elements are subjected to heat to render the backing readily flowable under pressure with relation to

the printing shell. The mechanism is however adapted to form printing plates constructed in other manner, as by stereotyping, or other methods.

The printing plate elements are subjected 70 to heat of such degree and throughout such period of time as will effect a spongy condition of the backing material, that is, a heat condition in the backing material which is near its point of fusion, and the means 75 provided for heating the printing plate elements are admirably adapted for such purposes and for providing such temperature uniformly throughout the area of the printing plate. The effect produced upon the 80 printing plate in the operation of the device is more fully shown, described and claimed in the aforesaid application Serial No. 145,881, to which reference is respectfully made for further exposition of the 85 same.

Referring to the drawings, 31 represents a table arranged to be heated uniformly throughout, as by partially immersing the same in a bath 32, in a melting pot 90 33, suitable means being provided for heating the pot, shown as gas-burners 34, formed for instance of perforated pipes under the pot, fed from a suitable source of supply, and controlled by valves 35, discharging into 95 gas and air mixers 36, for regulating the temperature applied to the melting pot.

The table is exemplified as supported in the pot on suitable blocks 37 suitably secured with relation to the frame of the machine, for positioning the table.

The bath 32 is preferably of a material which, when cold, is a solid, and having a fusing point somewhat similar to the fusing point of the backing material of the 100 printing plate, and is rendered fluid by the heat to which the melting pot is subjected.

This bath may be exemplified as a mixture of lead, tin and antimony, in the proportion of ninety pounds of lead to five pounds each 110 of tin and antimony, the fusing point of the mixture being approximately 600 degrees Fahrenheit. This mixture may be employed when the backing material of the printing plate is of a substantially similar mixture. If desired the bath may be a different mixture or composition, dependent on the composition of the backing material, which latter may for instance be gutta percha, or other material which is a solid when of atmospheric temperature and is rendered fluid by heat.

The fusing point of the backing material is less than that of the printing shell. The printing shell may be instanced as of copper, 125 whose fusing point is approximately 1900 degrees Fahrenheit.

In the present exemplification, the heat is transmitted to the printing plate through the table 31 and a flexible band 41 herein- 130

after described, which may, for example, be a band of cold rolled steel, and a cushioning layer 42 between the printing plate and the flexible band, which cushioning layer 5 may be a sheet of paper. The printing plate is laid upside down upon the flexible band the printing surface being presented to the cushioning layer, when said cushioning layer is employed.

10 The frame of the machine is shown at 43 and comprises a pedestal 44. The frame is shown as including the melting pot.

It is the intention to curve the printing plate on a sector of a cylinder to conform to 15 the usual plate cylinders to which curved printing plates are arranged to be attached by suitable well-known locking means.

In the present exemplification, a pluri-part mold is employed, about which the 20 printing plate is curved, the printing plate being located between the flexible band 41 and said mold while subjecting the same to the bending or curving operation. The mold-sections are exemplified at 46, 47.

25 The ends of the band are articulated by hinges 49, 50, to opposite ones of the mold-sections, at least one of the hinges being releasable, as by releasing the pintles 51 from the straps of the hinges respectively on the 30 mold-sections and flexible band. The mold-sections are provided with arc faces 52, which, when the mold-sections are brought together, are continuations of one another for forming a composite mold having a bending 35 face formed as a sector of the cylinder having a radius approximately the length of the radius of the plate-cylinder to which the printing plate is arranged to be secured, preferably making allowance for enabling 40 a slight finishing cut to be taken off of the rear face of the backing of the printing plate.

The curving of the printing plate is effected progressively along the curvature in 45 lines parallel with the axis of the curvature equi-distantly from the median line of the plate parallel with said axis. Excess pressure upon the plate perpendicular to its printing surface is also preferably avoided.

50 In the exemplification, these objects are accomplished by providing the mold-sections with gear-segments 54 at the respective ends of the mold-sections, which segments mesh with toothed racks 56 on the machine frame, so that when the mold-sections are moved toward and from one another their parallelism is maintained. This construction also insures that the distance between the hinges 49, 50, is maintained.

60 Proper relative movement between the flexible band and the mold-sections with relation to each other and the length of the flexible band, and proper spacing between the flexible band and the arc faces of the

mold-sections are also maintained, this latter 65 spacing being preferably approximately the thickness of the printing plate, plus the cushioning layer 42, when the cushioning layer is employed.

Bearers 59, 60, are provided for the mold-sections, the bearers 59 being shown on the mold-sections and the bearers 60 at the respective edges of the table, the bearers having the purpose of insuring a proper space for the printing plate between the arc faces 75 of the mold-sections and the flexible band.

Rests 62 are provided on the frame, upon which the mold-sections rest when in separated relations or when moved to the limit of one of their directions of movement. 80

In order to maintain the mold-sections in proper relative positions when connected, pins 64 on the respective mold-sections are arranged to be received in holes 66 on the opposite mold-section. A latch 68 on one 85 of the mold-sections is arranged to be received by a catch 69 on the other mold-section for holding the mold-sections in connected relation when brought together.

The printing plate elements are preferably subjected to pressure during application of heat, and means are provided to bear the plate upon the heat-transmitting part in order to insure uniform distribution of heat throughout the printing elements. 90 Means for accomplishing this are exemplified as comprising presser-feet 70 adjustable on bearings 71 lengthwise of arms 72 and held in adjusted positions by set-screws 73. The arms are shiftable on their bearings 74 100 lengthwise of a rod 75 supported in brackets 76 extending from the frame of the machine. The arms and presser-feet are so positioned as to rest upon the rear faces of the printing plate opposite the bearers 25, 26, when pressing the latter. The arms are held in down position by means of latches 77 arranged to engage a holding-bar 78 on the frame.

When a plate of large area is operated on it is advisable to provide additional 110 presser elements acting upon the backing within the lines of the bearers 25, 26. Such additional presser elements are preferably of greater area than the presser-feet 70 in order to contact a greater area of the backing of the printing plate elements to limit indentation by the same when the backing is in heated condition. These latter presser means may, for instance, be presser shoes 80 on bearings 81 adjustable on an arm 82 115 and held in adjusted positions on the arm by set-screws 83, the arm being adjustable on its bearing 84 lengthwise of the rod 75 and provided with a latch 87 coacting with the holding-bar 78.

Uniform transmission of heat through the table and flexible band to the printing plate elements is thus insured. When the print-

ing plate elements are in proper heated condition, the latches 77, 87, are released and the arms 72, 82, moved out of range of the mold-sections prior to operation of the mold-sections for curving the plate, as by swinging the same upwardly from the plate upon their bearings 74, 84. The arms 72, 82, may be counterweighted on the rod 75 by means of counterweights 79, 89.

- 10 The printing plate is desirably so positioned with relation to the bending elements that contact between the bending elements and the respective edges of the printing plate will be simultaneously effected along lines parallel to the axis of curvature of the printing plate when curved which axis is either parallel with or perpendicular to the upright position of the printing lines indicated at 88, on the printing plate, so that 15
- 20 when the curved printing plate is arranged upon the plate-cylinder of the printing press, the printing face will be upright upon the printed sheet. For accomplishing this the said edges, representing the top and bottom edges 85 of the printing plate have been 25 trimmed parallel with each other and with the axis of the plate, and the side edges 86 of the printing plate have also been trimmed perpendicular to the edges 85.
- 30 In order to position the printing plate equidistantly from the respective mold-sections and in the middle of the table, gages 91 are provided, the gages being adjustable lengthwise on arms 92 and held in adjustable 35 positions by set-screws 93, the arms 92 being adjustable laterally, and swingable on their bearings 94 on the rod 75 to move them out of range of the mold-sections during the bending operation. The arms are counter-weighted by counterweights 99 for raising the same, and with latches 97 for coacting with the bar 78 for holding the same in down position.

40 The arms 92 are arranged to be depressed by means of a handle 95 and are operable independently of the arms 72, 82.

45 In positioning the plate, the plate is laid face down on the band, and the arms 92 brought downwardly and latched so as to place the gages 91 above the band. The side edge of the plate is then guided against the gages, whereby the axis of the plate, when curved, is brought into parallelism with the axes of the mold-sections. The back of the 50 plate is provided with a mark 96 which coincides with the median line of the plate. The band is provided with a centering mark 98 with which the mark 96 is brought into registry.

55 The plate is positioned as stated, whereupon the presser means described are brought to bear upon the plate. Thereupon the gages 91 are raised by releasing the latches 97. The plate is subjected to the

heat as hereinbefore described. When the 65 plate or plate elements have been properly heated, the latches 77, 87, are released for raising the arms 72, 82, out of range of the path of the mold-sections.

60 It will be now apparent that when the 70 mold-sections are moved toward each other, the mold-sections being subjected to equal movement, that equal end pressure or contact will be made simultaneously with both ends of the plate being bent, (see Fig. 12,) 75 the curving action taking place in lines parallel to the median line of the plate, so that the printing lines will be in correct relation with the curvature of the plate.

70 When rolling over the mold-sections for 80 bending the printing plate, the bending band will have a tendency to remain flat upon the supporting surface of the table and to bend on the arc of a circle as the ends of the mold-sections, to which the ends of 85 the band are secured, are raised from the table, thereby forming a space 100 of uniform depth throughout the bearing surface of the mold between said bearing surface and the band, in which the printing plate 90 being formed is located.

75 The first contact between the mold-sections and the printing plate, when bending the plate, is made preferably simultaneously with the opposite ends of the printing plate, 95 as exemplified in Fig. 12, such contact with said ends pinching said ends between the mold-sections and the flexible band sufficiently to maintain the ends of the plate at its printing surface against separation, 100 forming limiting means for preventing separation between the ends of said plate, the movement of the mold-sections toward each other continuing until the flexible band and the printing plate thereon are curved about 105 and upon the mold-sections, the inner faces of the mold-sections meeting and the mold-sections being secured together by the latch 68 for forming a unitary mold, for instance 110 as exemplified in Fig. 1. This movement of the mold-sections to curve the printing plate is preferably a uniform and a comparatively rapid movement.

80 Upon the curving of the printing plate being accomplished, it is preferably subjected to pressure, accomplished by a rolling back and forth of the united mold-sections upon the table, whereby the printing plate is rolled between the flexible band and the mold-sections to insure a uniform conformity of the inner face of the printing plate with the curvature of the mold, this curvature being preferably a curvature approximating the curvature of the plate cylinder 115 upon which the printing plate is to be secured, allowing preferably for a slight shaving to be taken off of the inner face of the printing plate to remove any irregularities 120 125

of surface which may be present due, for instance, to the heating and bending of the backing. The bearers 59, 60, prevent excess pressure upon the printing plate.

- 5 The initial pressure of the mold-sections upon the plate is preferably borne by the end bearers 25 on the printing plate. The segment gears 54 and toothed rack 56 insure parallelism of the mold with the table in 10 all assumed positions of the mold during rolling.

Means are provided for subjecting the plate being formed to the action of a cooling agency, exemplified as a body 101 of 15 fluid, for instance, water, in each of the mold-sections, which are formed hollow for the purpose, the water being fed into the mold-sections by inlet pipes 102 and received from the mold-sections by outlet 20 pipes 103, these respective pipes communicating with flexible pipes 104, 105, of desirable length and positioned to permit the proper rolling of the mold sections. Valves 106 are employed to regulate the flow of the 25 water and to regulate the temperature of the same in the mold sections.

In the present exemplification of the method, the heated backing element is in compressible condition, being for instance 30 spongy due to the heat application, that is, readily flowable under pressure with relation to the printing shell. The printing shell during the curving operation retains its dimensions, so that the printing surface 35 of the completed curved printing plate is the same as the printing surface before the curving. The spacings between printing lines are maintained, so that a printed impression taken from the plate after being 40 curved is the same as a printed impression taken from the printing surface when in the flat, or differently expressed, the printing surface of the curved plate laid out in plane is of the same dimensions as the printing 45 surface when flat. A stretching of the printing surface during curving is avoided. The material of the backing accommodates itself to the curvature, the molecules thereof undergoing rearrangement due to the character 50 of the heating and curving action in the present exemplification, resulting in a curved printing plate in which the metal is not buckled or strained, so that the inner 55 face of the curved printing plate lies snugly throughout its area against the periphery of the plate-cylinder, without hollow spots thereunder.

Thus referring to Fig. 9 the ends of the plate are perpendicular to the plane of its 60 printing face. When the plate has been curved, these ends are radial to the sector of the cylinder formed by the plate. (See Figs. 7 and 13.)

The depressions 29 are exemplified as 65 grooves for forming ribs 111. They may

be formed in the backing prior to curvature in any desired manner, either while the backing is being made, or by cutting the same into the backing after being made. The walls of the depressions preferably meet 70 at a sharp angle at the bottoms of the depressions to aid in regularity of curvature of the printing surface.

When the curving of the plate has been accomplished, the bearers 25, 26, are trimmed 75 from the plate, for instance in the line of the grooves 27, 28, between said bearers and the printing surface.

The ends of the plate are then provided with suitable attaching faces, as see the 80 faces 112, for securing the plate to the plate-cylinder.

Having thus fully described my invention, what I claim as new and desire to secure by Letters Patent, is:

1. In a machine for curving printing plates, the combination of means including a mold composed of a plurality of sections having curved peripheries and arranged for contacting opposite ends of a plate to be 90 curved, means whereby to revolvingly move said sections toward one another and means for wrapping said printing plate about the mold-sections.

2. In an apparatus for curving printing 95 plates, the combination of a flexible band, and mold-sections having curved surfaces between which and said band the plate to be bent is arranged to be received, means whereby to revolvingly move said sections 100 toward each other and connections between said flexible band and said mold sections whereby the band is arranged to curve the printing plate about the mold-sections.

3. In an apparatus for curving printing 105 plates, the combination of a flexible band arranged to receive a printing plate to be bent thereon, mold-sections having surfaces about which a printing plate is capable of being curved and connections connecting 110 said mold-sections and said band, there being a printing plate space between said band and mold-sections located between said connections, and said mold-sections arranged to be revolvingly moved toward one another, 115 whereby the band with the printing plate to be curved are bent about said mold-sections.

4. In an apparatus for curving printing 120 plates, the combination of a flexible band arranged to receive a printing plate to be bent thereon, means for heating the printing plate, mold-sections having surfaces about which a printing plate is capable of being curved, and connections connecting 125 said mold-sections and said band, there being a printing plate space between said band and mold-sections located between said connections, said mold-sections arranged to be revolvingly moved toward one another, 130

whereby the band with the printing plate to be bent are bent about said mold-sections.

5. In an apparatus for bending printing plates, the combination of a flexible band arranged to receive a printing plate to be bent thereon, means for heating the printing plate, mold-sections having surfaces about which a printing plate is capable of being curved, connections connecting said mold-sections and said band, there being a printing plate space between said band and mold-sections located between said connections, said mold-sections arranged to be moved revolvingly toward one another, whereby 10 the band with the printing plate to be bent are bent about said mold-sections, and means for cooling said mold-sections.

6. In a machine for curving printing plates, the combination of a flexible band, 20 mold-sections having surfaces capable of having a printing plate curved thereabout between which and said band the printing plate to be curved is received, and means whereby said mold-sections are revolvingly movable toward each other and said band is wrapped progressively from both sides of its middle toward its middle about said mold-sections.

7. In a machine for curving printing plates, the combination of a flexible band, 30 mold-sections having surfaces capable of having a printing plate curved thereabout between which and said band the printing plate to be curved is received, means for heating said printing plate, and means whereby said mold-sections are revolvingly movable toward each other and said band is wrapped progressively from both sides of its middle toward its middle about said mold sections.

8. In a machine for curving printing plates, the combination of a flexible band, mold-sections having surfaces capable of 45 having a printing plate curved thereabout between which and said band the printing plate to be curved is received, means for heating said printing plate, means for applying pressure to said printing plate during the heating thereof, and means whereby 50 said mold-sections are revolvingly movable toward each other and said band is wrapped progressively from both sides of its middle toward its middle about said mold-sections.

9. In a machine for curving printing plates, the combination of a flexible band, mold-sections having surfaces capable of 55 having a printing plate curved thereabout between which and said band the printing plate to be curved is received, means for heating said printing plate, means whereby 60 said mold-sections are revolvingly movable toward each other and said band is wrapped progressively from both sides of its middle toward its middle about said mold-sections, 65 and cooling means for said mold-sections.

10. In a machine for curving printing plates, the combination of a flexible band, mold-sections having surfaces capable of having a printing plate curved thereabout between which and said band the printing plate to be curved is received, means acting 70 on said mold-sections and said flexible band whereby said mold-sections are revolvingly movable toward each other and said band is wrapped progressively from both sides of 75 its middle toward its middle about said mold-sections, and means for rolling said band and mold-sections.

11. In a machine for curving printing plates, the combination of a flexible band, 80 mold-sections having surfaces capable of having a printing plate curved thereabout between which and said band the printing plate to be curved is received, means for heating said printing plate, means for applying pressure to said printing plate during the heating thereof, means whereby said 85 mold-sections are rockingly movable toward each other to wrap said band progressively from both sides of its middle toward its 90 middle about said mold-sections and for rolling said band and mold-sections.

12. In an apparatus of the character described, the combination of a flexible band, mold-sections coacting with said band, a 95 support for said band, and bearing means for said mold-sections whereby a printing plate space is formed between said band and mold-sections, said mold-sections movable toward one another with a rolling motion. 100

13. In an apparatus of the character described, the combination of a flexible band, mold-sections coacting with said band, a support for said band, bearing means for said mold-sections whereby a printing plate 105 space is formed between said band and mold-sections, said mold-sections movable toward one another with a rolling motion, and means for connecting said mold-sections, said connected mold-sections rollable on said 110 bearing means.

14. In an apparatus of the character described, the combination of a flexible band, mold-sections coacting with said band, a support for said band, bearing means for 115 said mold sections whereby a printing plate space is formed between said band and mold-sections, said mold-sections movable toward one another with a rolling motion, and means for maintaining said mold-sections parallel. 120

15. In an apparatus of the character described, the combination of a flexible band, mold-sections coacting with said band, a support for said band, bearing means for 125 said mold-sections whereby a printing plate space is formed between said band and mold-sections, said mold-sections movable toward one another with a rolling motion, gear-segments on said mold-sections, and coacting 130

toothed racks, for maintaining said mold-sections parallel.

16. In an apparatus of the character described, the combination of a plurality of 5 coacting mold-sections, a flexible band movable with said respective mold-sections, a table for said band, bearing supports for said mold-sections, means for moving said mold-sections toward one another with a 10 rolling motion and for bending said band and the printing plate between it and said mold-sections about said mold-sections, and means for connecting said mold-sections, and constructed whereby to roll said connected 15 mold-sections with said band and the printing plate between said mold-sections and the band on said table.

17. In an apparatus of the character described, the combination of a plurality of 20 coacting mold-sections, a flexible band movable with said respective mold-sections, a table for said band, heating means acting on said table, bearing supports for said mold-sections, means for moving said mold-sections toward one another with a rolling motion and for bending said band and the printing plate between it and said mold-sections about said mold-sections, and means for connecting said mold-sections, and constructed whereby to roll said connected 25 mold-sections with said band and the printing plate between said mold-sections and the band on said table.

18. In an apparatus of the character described, the combination of a plurality of 30 coacting mold-sections, a flexible band movable with said respective mold-sections, a table for said band, heating means acting on said table, bearing supports for said 35 mold-sections, means for moving said mold-sections toward one another with a rolling motion and for bending said band and the printing plate between it and said mold-sections about said mold-sections, cooling 40 means acting on said mold-sections, and means for connecting said mold-sections, and constructed whereby to roll said connected 45 mold-sections with said band and the printing plate between said mold-sections and the band on said table.

19. In an apparatus of the character described, the combination of a flexible band, mold-sections, means for connecting said band to said respective mold-sections, a table 50 for said band, bearing means for said mold-sections whereby a printing plate space is formed between said band and mold-sections, means whereby to move said mold-sections toward one another for wrapping said band about said mold-sections arranged whereby the opposite ends of said printing plate are held against endwise movement between said band and mold-sections and whereby to roll said band on said table and said connected 55 mold-sections on said bearing means.

20. In an apparatus of the character described, the combination of a flexible band, mold-sections, means for connecting said band to said respective mold-sections, a table for said band, bearing means for said mold-sections whereby a printing plate space is formed between said band and mold-sections, said mold-sections movable toward one another with a rolling motion for wrapping said band and the printing plate about said 70 mold-sections, and for rolling said band on said table and said connected mold-sections on said bearing means, gears on said mold-sections, and toothed racks coöperating therewith for maintaining said connected 75 mold-sections parallel throughout said rolling movements.

21. In an apparatus of the character described, the combination of a flexible band, mold-sections, means for connecting said 80 band to said respective mold-sections, a table for said band, heating means for said table, bearing means for said mold-sections whereby a printing plate space is formed between said band and mold-sections, said mold-sections movable toward one another with a 85 rolling motion for wrapping said band and the printing plate about said mold-sections, and for rolling said band on said table and said connected mold-sections on said bearing 90 means, gears on said mold-sections, and toothed racks coöperating therewith for maintaining said connected mold-sections 95 parallel throughout said rolling movements.

22. In a machine of the character described, the combination of a table, bearers, heating means for said table, and rollable plate curving means supported over said table by said bearers.

23. In a machine of the character described, the combination of a heat transmitting table arranged for supporting a printing plate, bearers at the sides of said table, heating means for said table, rollable plate curving means supported over said table by 105 said bearers, equalizing racks extending lengthwise of said bearers, and gear-segments carried by said plate curving means coacting with said equalizing racks.

24. In a machine of the character described, the combination of a heat transmitting table arranged for supporting a printing plate, bearers at the sides of said table, a melting pot in which said table is received, plate curving means supported through said 110 bearers, and heating means for said melting pot.

25. In a machine of the character described, the combination of a heat transmitting table arranged for supporting a printing plate, movable means for pressing the printing plate toward said table, bearers at the sides of said table, a melting pot in which said table is received, rollable plate curving means supported through said bearers, and 125 130

adjustable heating means for said melting pot, and constructed whereby said movable means and said plate curving means are arranged to act in sequence on the printing plate.

26. In a machine of the character described, the combination of a flexible band, mold-sections having surfaces about which a printing plate is capable of being curved between which and said band the printing plate to be bent is arranged to be received, means whereby the sections of said mold are movable revolvingly toward each other whereby said band is arranged to bend the printing plate about said mold-sections, and a lock between said mold-sections.

27. In a machine of the character described, the combination of a flexible band, mold-sections having surfaces about which a printing plate is capable of being curved between which and said band the printing plate to be bent is arranged to be received, means whereby the sections of said mold are movable with a rolling motion toward each other, whereby said band is arranged to bend the printing plate about said mold-sections, a lock between said mold-sections, a support for said band, and equalizing means for said mold-sections permitting rolling of said mold and band on said support and maintaining the position of the axis of said mold parallel during the rolling movement of said mold.

28. In a machine for curving printing plates, the combination of mold-sections, having surfaces about which a printing plate is capable of being curved, a flexible band, means for causing said mold-sections and flexible band to move together, means whereby to move said mold-sections toward each other with a rolling motion with the printing plate between said flexible band and said mold-sections, and arranged to hold the ends of the printing plate between said mold-sections and flexible band for limiting endwise separation between the ends of said printing plate and arranged for wrapping said flexible band and said printing plate to be curved about said mold-sections by movement of said mold-sections toward each other.

29. In a machine for curving printing plates, the combination of mold-sections having surfaces about which a printing plate is capable of being curved, a flexible band, means for causing said mold-sections and flexible band to move together, means whereby to move said mold-sections toward each other with a rolling motion with the printing plate between said flexible band and said mold-sections, and arranged to hold the ends of the printing plate between said mold-sections and flexible band and arranged for wrapping said flexible band for limiting endwise separation between the ends of said printing plate and said printing plate to be

curved about said mold-sections by movement of said mold-sections toward each other, and cooling means for said mold-sections.

30. In a machine for curving printing plates, the combination of a flexible band arranged to receive the printing plate to be curved, normally separated mold-sections with which said flexible band has connections, said flexible band arranged for receiving a printing plate to be curved thereover, movable gaging means between said mold-sections for gaging the position of the printing plate to be curved with relation to said flexible band and separated mold-sections, and means for causing movement of said mold-sections toward each other in parallel lines for wrapping said flexible band and printing plate to be curved about said mold-sections, and constructed whereby said movable gaging means and said mold-sections are arranged to act in sequence on the printing plate.

31. In a machine for curving printing plates, the combination of a flexible band arranged for receiving a printing plate to be curved thereover, normally separated mold-sections coating with said flexible band for curving the printing plate, heating means for heating said flexible band whereby said printing plate to be curved is heated, movable presser means arranged to extend between said mold-sections pressing said printing plate to be curved toward said flexible band, means whereby said presser means are moved free from the path of said mold-sections, and means whereby said mold-sections are caused to approach each other in parallel lines for wrapping said flexible band and the printing plate to be curved about said mold-sections, and constructed whereby said movable presser means and said mold-sections are arranged to act in sequence on the printing plate.

32. In a machine for curving printing plates, the combination of a flexible band, normally separated mold-sections with which said flexible band has connections, said flexible band provided with a gaging mark whereby to gage the position of the printing plate to be curved equidistantly from said mold-sections, movable gaging means for positioning the printing plate to be curved parallel with said mold-sections, means whereby said last-named gaging means are moved free of the path of said mold-sections, and means for causing parallel movement of said mold-sections toward each other for wrapping said flexible band and the printing plate to be curved about said mold-sections, and constructed whereby said movable gaging means and said mold-sections are arranged to act in sequence on the printing plate.

33. In a machine for curving printing

- plates, the combination of a flexible band, normally separated mold-sections, means for heating said flexible band, said flexible band provided with a gaging mark whereby to 5 gage the position of the printing plate to be curved equidistantly from said mold-sections, movable gaging means for positioning the printing plate to be curved parallel with said mold-sections, means whereby said last- 10 named gaging means are free of the path of said mold-sections, presser means between said mold-sections causing pressure on said printing plate to be curved toward said flexible band, means for causing movement of 15 said presser means free of the path of said mold-sections, and means for causing parallel movement of said mold-sections toward each other for wrapping said flexible band and the printing plate to be curved about 20 said mold-sections, and constructed whereby said gaging means and said pressure means are arranged to act on the printing plate in sequence with said mold-sections.
34. In a machine for curving printing 25 plates, the combination of normally separated mold-sections separated for reception of the printing plate to be curved, and adjustable gaging means for positioning the printing plate to be curved in the space be- 30 tween said separated mold-sections relatively to said mold-sections mounted for being removably received in said space.
35. In a machine for curving printing 35 plates, the combination of normally separated mold-sections, separated for the reception of the printing plate to be curved, a table, a heater for said table whereby said printing plate is heated, and movable adjustable presser means for said printing 40 plate removably received in the space be- 45 tween said separated mold-sections, said mold-sections arranged for relative approach for curving the printing plate, and constructed whereby said movable adjustable presser means and said mold-sections

are arranged to act in sequence on the printing plate.

36. In a machine for curving printing 50 plates, the combination of normally separated mold-sections, separated for the reception of the printing plate to be curved, pivoted arms, gages for the printing plate adjustable lengthwise of said arms, means for releasably securing said arms in the space between said separated mold-sections, and 55 means for automatically swinging said arms on their pivots into inactive relation upon release of said securing means.

37. In a machine for curving printing 60 plates, the combination of normally separated mold-sections, separated for the reception of the printing plate to be curved, pivoted arms, pressers for the printing plate adjustable lengthwise of said arms, means for releasably securing said arms in the space 65 between said separated mold-sections, and means for automatically swinging said arms on their pivots into inactive relation upon release of said securing means.

38. In a machine for curving printing 70 plates, the combination of normally separated mold-sections, separated for the reception of the printing plate to be curved, pivoted arms arranged to be received in the space between said separated mold-sections, 75 latches for securing said arms in said space, gages and pressers for the printing plate respectively adjustable on said respective arms, latches of which arms are separately releasable, and means for automatically 80 swinging said arms out of said space upon release of said respective latches.

In testimony whereof, I have hereunto signed my name in the presence of two subscribing witnesses.

LESLIE W. CLAYBOURN.
